UNITED STATES PATENT OFFICE.

BENJAMIN F. BROWNLOW, OF PORTLAND, OREGON.

NAPKIN-FOLDING MACHINE.

1,371,349.

Specification of Letters Patent. Patented Mar. 15, 1921.

Application filed May 7, 1919. Serial No. 295,309.

To all whom it may concern:

Be it known that I, BENJAMIN FRANKLIN BROWNLOW, a citizen of the United States, residing at Portland, in the county of Multnomah and State of Oregon, have invented, 5 a new and useful Napkin-Folding Machine, of which the following is a specification.

My invention relates to improvements in napkin folding machines in which a square 10 piece of paper or cloth is inserted at one end of the machine to issue at the other end neatly folded in the familiar triangular shape.

The objects of my invention are to produce 15 a cheap and simple mechanism which will save the labor of folding napkins by hand.

I attain these objects with the mechanism illustrated in the accompanying drawing in 20 which—

Figure I is a plan view of the entire apparatus.

Fig. II is a section of Fig. I along the line *a—a*,

Fig. III is a section of Fig. I along the line *b—b*,

Fig. IV represents a piece of paper or cloth before entering the machine with the folding edge shown in dotted lines, and

Fig. V illustrates on a somewhat larger scale the appearance of Fig. IV after having emerged from the machine.

Similar numerals refer to similar parts throughout the several views.

A single piece of sheet metal is wound spirally into a truncated cone 1 so that a double-walled housing is produced. This cone 1 is laid on its side on a table 2 and fastened thereto by suitable flanges 3.

A carrier belt 4 proceeds within the double walls from the base toward the vertex, and a napkin 5 inserted with one corner between carrier belt and the inner wall 6 will emerge as a spirally shaped cone to be flattened out 45 into Fig. V by the two rollers 7 and 8.

After passing said two rollers the folded napkin slides down the inclined apron 9 into a suitable storage receptacle 10.

At the tail end the carrier belt 4 is supported by pulley 11, shaft 11 and bearings 12, at the head end by pulley 13, shaft 13 and bearings 14. Shaft 13 may be driven 50 by pulley 15 from a motor (not shown),

and the roller 7 is driven from the shaft 13 by means of a chain or belt 16. Gear 17 55 imparts rotation from the roller 7 to roller 8.

Having described my invention it will be seen that my objects have been accomplished and, though I have shown the preferred form of construction, I reserve to myself 60 the right to make minor changes, providing I do not violate the spirit and principle of my invention.

I claim:

1. In a napkin folding machine, the combination of a supporting table, a housing in the shape of a truncated cone lying with its side on the table, a carrier belt passing through the housing from the base toward the apex, a pair of horizontal rolls at the 70 apex of the conical housing, an inclined apron adjacent to the rolls, and a receptacle adjacent to the apron, the whole device adapted to roll a sheet of paper into a cone, flatten the cone and deposit it into the receptacle, substantially as, and for the purpose set forth.

2. In a napkin folding machine, the combination of a supporting table, a truncated cone lying with its side on the table, said 80 cone being a metal strip spirally wound into a double walled housing, a carrier belt secured below the table, the upper run of said belt passing between the double walls of said housing, adapted to carry a sheet of 85 paper cornerwise through the housing and transform it into a cone, and a pair of horizontal rolls disposed at the apex of the cone to flatten the paper cone, substantially as, and for the purpose set forth.

3. In a napkin folding machine, the combination of a supporting table, a truncated cone formed of a spirally wound strip of metal lying with its side on the table, said spirals forming a double walled housing, 95 with a carrier belt passing between the double walls of said housing from the base toward the apex, and a pair of horizontal rolls disposed at the apex of the cone, revolving at the same circumferential velocity 100 as the carrier belt, and adapted to flatten a cloth or paper cone emerging from the housing, substantially as, and for the purpose set forth.

B. F. BROWNLOW.
